UNITED STATES PATENT OFFICE.

ALFRED E. MAAGE, OF MILWAUKEE, WISCONSIN, ASSIGNEE TO THE CUTLER-HAMMER MFG. CO., OF MILWAUKEE, WISCONSIN, A CORPORATION OF WISCONSIN.

ELECTRIC SWITCH.

Application filed November 24, 1919. Serial No. 340,279.

To all whom it may concern:

Be it known that I, ALFRED E. MAAGE, a citizen of the United States, residing at Milwaukee, in the county of Milwaukee and 5 State of Wisconsin, have invented new and useful Improvements in Electric Switches, of which the following is a full, clear, concise, and exact description, reference being had to the accompanying drawing, forming 10 a part of this specification.

This invention relates to electric switches. More particularly this invention relates to electric switches comprising relatively movable operating and operated members subjected to the action of an energy storing spring which serves to hold the latter during a given relative movement of the former and to move the latter with a snap action upon continued movement of the former, as for example, a switch comprising 20 concentrically pivoted members connected by a helical spring to be shifted across the common pivot point thereof by movement of one.

Switches of the aforesaid type while possessing numerous advantages are open to the objection that the spring connected members at a certain instant during each operation occupy relative positions rendering the 30 spring ineffective to bias the same relatively with the result that if said members happen to stick in such a relation the snap action of the switch may be defeated.

The present invention has among its objects to overcome such disadvantages of switches of the aforesaid type and to provide a switch of such type including means to positively prevent defeat of its snap action from such a cause.

Another object is to provide means for the aforesaid purpose which will tend to accentuate the snap action of such switches.

Other objects and advantages will hereinafter appear.

In the accompanying drawing, wherein is illustrated an embodiment of the invention, Figure 1 is a side elevational view partly in section thereof;

Fig. 2 is a front view, also partly in section, of the same; while,

Fig. 3 is a rear view thereof.

Referring to the drawing, the same illustrates a substantially cylindrical base 1 composed of suitable insulating material having 55 at its respective ends recesses 2 and 3 sepa-

rated by a central web or partition 4. Said partition is provided with an axially located bore in which is mounted a bearing 5 carrying an elongated and relatively rotatable sleeve 6, said sleeve in turn carrying a rotatable spindle 7. A contacting member 8 is riveted or otherwise rigidly secured to one end of spindle 7 and adapted to oscillate therewith, being insulated therefrom by suitable washers 9. Said contactor is adapted in one position to engage and bridge suitable fixed contacts 10 and 11 located within the recess 2 and provided with conductor terminals. The switch operating mechanism is associated with the opposite 60 end of the spindle 7 and located within the recess 3.

Said operating mechanism comprises an arm 12 rigidly secured to the spindle 7, an operating member 13 mounted upon or 70 formed integral with the sleeve 6 and a helical tension spring 14 terminally secured to the respective outer ends of said arm and said operating member. Suitably located stops are formed upon the sides of the recess 3, or otherwise provided, for arresting movement of said arm and said operating member in either direction in proper relations to one another and to the fixed contacts. 80

The spring 14 serves to bias said arm and said operating member to move toward each other for all positions of said elements except that in which the same are in joint alignment. Also upon actuation of the operating member from either of its extreme positions said spring serves to maintain the arm 12 in its corresponding extreme position until said spring has been shifted beyond its position of alignment with said arm, 90 the stored energy of said spring thereafter serving to throw said arm to its opposite extreme position with a snap action.

A substantially conical restraining device 15, which in practice may be formed integral 100 and coaxial with the spindle 7, is arranged to extend within and partially across the path of movement of said spring.

During operation of the switch in either direction movement of the spring is temporarily retarded by said restraining device, whereby the operating member 13 and said spring do not pass simultaneously through the position of alignment with the arm 12. And it is thereby rendered impossible to de- 105 110

feat the snap action by arresting movement of the operating member in a position where-in the forces acting upon said arm 12 are balanced.

5 Also the action of the restraining device forces the central portion of the spring axially of the spindle 7 whereby the tension and stored energy of said spring are materially augmented. Such energy moreover is 10 released with great abruptness as the spring passes the apex of said restraining device. Further since the operating member moves in advance of the spring, the former at the instant of such release has necessarily moved 15 out of alignment with the arm 12 and into a position relative thereto affording an increased mechanical advantage to the action of such force.

Considering the structure of the switch 20 operating mechanism more in detail, the spindle 7 is provided within the recess 3 with a pair of parallel and symmetrically located transverse notches 16 whereas the arm 12 is provided with a longitudinal open ended slot 25 17 for permitting said arm to be moved radially into assembly with said spindle, the sides of said slot being adapted to fit within said notches whereby said elements when assembled are adapted to move in unison. The 30 free end of said arm is provided with an up-standing lug 18 adapted to receive and hold the end of the spring 14 the tension of the latter serving to maintain said arm and spindle in assembled relation.

35 The operating member 13 is substantially U-shaped and provided at one end with an opening adapted to fit snugly about the end of the sleeve 6 being held against axial movement relative thereto by means of a shoulder 40 19 and a bead 20 of the latter. The central portion of said operating member is provided with an instruck lug 21 adapted to receive the opposite end of the spring 14. The opposite terminal portion of said arm is provided 45 with an outward extension 22 arranged substantially coaxial with the spindle 7, said lug affording anchorage for a turn key 23 or other suitable actuating device.

In practice the switch operating mechanism is preferably enclosed by a cap 24 adapted to fit snugly over the adjacent end of the base 1 being conveniently applied prior to attachment of the actuating device 23 with the operating member 13.

55 What I claim as new and desire to secure by Letters Patent is:

1. The combination with relatively movable members, one of the same being oscillatable, of a spring associated with the latter 60 member to oscillate the same with a snap action upon reverse operations of the other of said members and to hold said oscillatable member against movement during a given initial movement of the other member in 65 either direction and means acting upon said

spring to prevent the same from being rendered inactive through relative positioning of said member.

2. The combination with relatively movable members, of a spring associated with 70 said members to move one of the same with a snap action upon actuation of the other, such coaction of said elements involving a tendency thereof to assume a transient relation neutralizing the action of said spring, and means coacting with certain of said elements to insure against such relative positioning of said elements.

3. The combination with relatively movable members, one of the same being oscillatable about a fixed axis, of a spring associated with said latter member to oscillate the same with a snap action upon reverse operations of the other of said members and to hold said oscillatable member against 80 movement during a given initial movement of the other member in either direction, and means acting upon said spring to prevent the same from being rendered inactive through 85 relative positioning of said members.

4. The combination with relatively movable members, one of which is pivotally mounted, of a helical spring connected to 90 said members to be shifted across the axis of said pivoted member by relative movement of the other of said members and a device acting on said spring to distort its axis while moving across the axis of said pivoted member to thereby maintain said spring active at all times for biasing said members relatively.

5. The combination with a pair of members adapted to oscillate with reference to a common axis, of a spring to be moved 105 by one of said members across said axis for effecting snap movement of the other of said members, and means providing against positioning of said spring in co-planar relation to said axis.

6. The combination with a contacting member and an operating member adapted to oscillate with reference to a common axis, of a spring operable by the latter member to effect snap movement of the former, said operating member and said spring being movable jointly and tending when so moved to pass simultaneously through a position of radial alignment with said contacting member, and means providing against simultaneous radial alignment of said operating member and said spring.

7. The combination with a contacting member and an operating member adapted to oscillate with reference to a common axis, 115 of a spring operable by the latter member to effect snap movement of the former, said operating member and said spring being movable jointly and tending when so moved to pass simultaneously through a position 120 of radial alignment with said contacting 125 member.

member and means influencing movement of said spring to retard the same and to increase the tension thereof during passage of said operating member through such position of alignment.

8. The combination with a pair of members adapted to oscillate with reference to a common axis, of a spring operatively associated with said members, one of said members being movable to effect radial alignment of the terminal portions of said spring with respect to said axis, said spring being thereafter adapted to effect snap movement of the other of said members and means for effecting deflection of the central portion of said spring during such alignment of the terminal portions thereof for accentuating the subsequently effected snap action.

20 9. The combination with a pair of mem-

bers adapted to oscillate relatively with reference to a common axis, of a spring terminally connected to said members respectively, one of said members being movable through a position wherein the terminal portions of said spring are in radial alignment with respect to said axis for tensioning said spring, the latter being adapted thereafter to effect snap movement of the other of said members, and means for delaying initiation of said snap action pending further tensioning of said spring and pending arrangement of the terminal portions thereof with respect to said axis in a relation providing a strong mechanical advantage. 30 35

In witness whereof, I have hereunto subscribed my name.

ALFRED E. MAAGE.
